UNITED STATES PATENT OFFICE.

HERBERT TIDMARSH GEORGE, OF LONDON, ENGLAND, ASSIGNOR TO ARNOLD, CONSTABLE & CO., OF NEW YORK, N. Y.

DESIGN FOR CARPET.

SPECIFICATION forming part of Design No. 25,227, dated March 3, 1896.

Application filed January 27, 1896. Serial No. 577,066. Term of patent 3½ years.

To all whom it may concern:

Be it known that I, HERBERT TIDMARSH GEORGE, designer, a subject of the Queen of Great Britain, residing at 16 Dickenson Road, Crouch Hill, London, N., England, have invented and produced a new and original Design for Carpet, of which the following is a specification, reference being had to the accompanying drawing, making a part of the same, and is sufficient to enable others skilled in the art to make and use my invention.

What I claim as new, and desire to secure by Letters Patent, is—

1. In a design for a carpet, the body A substantially as shown. 15
2. In a design for a carpet, border B substantially as shown.
3. The design for a carpet, consisting of a body A, and border B, substantially as shown.

HERBERT TIDMARSH GEORGE.
